UNITED STATES PATENT OFFICE.

WILLIAM F. HILFIKER, OF JAY COUNTY, INDIANA.

AUTOMATIC GRAIN-WEIGHER.

1,037,249.

Specification of Letters Patent.

Patented Sept. 3, 1912.

Application filed February 19, 1912. Serial No. 678,627.

To all whom it may concern:

Be it known that I, WILLIAM F. HILFIKER, a citizen of the United States, residing in Jay county, in the State of Indiana, have invented a new and useful Automatic Grain-Weigher, of which the following is a full, clear, and accurate specification and exposition, being such as will enable others to make and use the same with absolute exactitude.

The object of my present invention, broadly speaking, is to provide an automatic grain weigher which will be strong and durable in construction, positive in action, automatic in operation, and adapted to facilitate the sacking and the delivery of grain, the same being accomplished with certainty and precision.

Another object is to provide an automatic grain weigher which can be manufactured, installed, and sold at a comparatively low price, and at the same time being so constructed as to accomplish the work required thereof with certainty and precision and in a minimum of time.

Other specific objects and particular advantages of my invention will be brought out and made apparent in the course of the following specification and that which is new will be correlated in the appended claims.

One manner for the accomplishment of the objects of my invention in a practical manner is shown in the accompanying four sheets of drawings, in which,—

Figure 1 is a front elevation of my weigher complete. Fig. 2 is a central vertical sectional view of my weigher complete, same being taken on line 2—2 of Fig. 4. Fig. 3 is a rear elevation of my weigher complete, same being taken from the side opposite to that of Fig. 1. Fig. 4 is a top plan of the weigher, all of the parts thereof being shown in position. Fig. 5 is a top plan of the device after certain parts have been removed. Fig. 6 is a detail isometrical view of the scale bar and the weight. And Fig. 7 is a detail perspective view of the manually operable distributor.

Similar indices denote like parts throughout the several views of the four sheets of drawings.

In order that my invention may be more clearly understood and its advantages be properly appreciated, I will now take up a detailed description thereof, in which I will

set forth the invention as clearly and as comprehensively as I may.

The body or main frame of my device consists of the four corner members: members 1 and 2 being in the front, and members 3 and 4 being in the rear. Each of said members is substantially identical with the others, each being formed flat and having a slot extending from its upper end to approximately its center vertically. Connecting the members 1 and 2 are the respective upper and lower ties 5 and 6, and in like manner connecting members 3 and 4 are the ties 7 and 8. Also, connecting members 1 and 3 is the tie 9, and in like manner connecting members 2 and 4 is the tie 10. Said ties 9 and 10 are of considerable width, as they not only serve as ties but they serve a more important purpose, as will herein-after appear.

Numerals 11, and numeral 12, each denote a container or bucket, same being rectangular in cross section, and somewhat less in length than are the four corner members above referred to. Bucket 11 is of same width as are the members 1 and 3, between which it operates, filling the space therebetween; and in like manner the bucket 12 is of same width as are the members 2 and 4, between which it operates, filling the space therebetween. Said buckets are exact complements of each other in size and weight, except that they are oppositely disposed with relation to each other. The bottoms ⁹⁰ *a* and *b* of the respective buckets 11 and 12 are disposed at angles as shown, sloping centerward as shown in Fig. 2. The inner wall of each of the buckets does not extend quite to the bottom of buckets, thereby providing outlets or mouths *c* and *d* in the vertex of each bucket, which are adapted to be closed by the respective ties 9 and 10 when the buckets are raised. The upper ends of the buckets are open, they being formed on the same angles as are the respective bottoms thereof.

Secured on the front and the rear edges of bucket 11 are the respective guide-blocks 13 and 14 which fit and are adapted to slide up and down in the slots of said members 1 and 3; and in like manner secured on the front and the rear edges of bucket 12 are the respective guide blocks 15 and 16, which fit and are adapted to slide up and down in the slots of said members 2 and 4. Said guide-blocks are of such length as to retain

the buckets in a vertical position at all times, and their positions are such as to form stops, preventing the buckets from dropping below a certain point. The highest limit to which the buckets 11 and 12 are adapted to move is with their upper ends located even with the upper ends of the corner members 1, 2, 3, and 4. Therefore it is apparent that the exits or mouths *c* and *d* are at all times closed by the ties 9 and 10, except when the buckets are at, or near, their lowest limits, at which latter time the said exits will be open, as they will then be below the ties 9 and 10.

15 The two buckets are adapted to counter-balance each other by the following means: Numeral 17 denotes a shaft which extends across between the ties 5 and 7, on which it rests. There is a notch formed in the center of the upper edges of the ties 5 and 7 and at the points of contact therewith the shaft 17 has V-shaped bearings which rest in said notches. Secured on the center of said shaft 17 is the sprocket-wheel 18. Numeral 19 denotes a sprocket chain, which operates over wheel 18, and the termini of said chain are secured to the centers of the inner faces of said buckets 11 and 12 as shown. From the above it is manifest that 20 the buckets counterbalance each other, and that the rotating of the shaft 17 will cause one bucket to descend as the other moves up.

25 Resting on the upper edge of the tie 5, extending upward and flaring apart, with their upper portions secured to inner portions of the corner members 1 and 2 which are beveled off that they may rest thereon, are the weight guides 20 and 21, against which the weight impinges, as will hereininafter be set forth. Secured on the forward end portion of shaft 17 is the block 22, which is secured on the squared portion of said shaft. Extending upward from the block 22 is the scale-bar 23, which has graduated 30 marks thereon which, in this instance, are numbered from "10" to "50", the smaller number being near the block 22. Slidably mounted on the said scale-bar is the weight 24, which is adapted to be secured at any point along the scale-bar by means of the winged-nut 25. Secured in the left and the right-hand faces of the weight 24 are the cushions *e* and *f*, respectively, which are adapted to contact with the respective guides 35 20 and 21. From the above it will be manifest that the farther the weight 24 is from the block 22 the more force will be required to throw weight 24 from one to the other of the guides 20 and 21.

40 The hopper comprises the front 26 and the rear 27. Connecting said front and rear, in their upper portions, are the two angularly disposed plates 28 and 29 which extend downward convergently, their lower edges being spaced slightly apart forming

45 the mouth *h*. Extending across and pivoted between the front and the rear of the hopper is the cut-off 30, same being carried on the shaft 31, which projects through the front 26. Also mounted between the front and the back of the hopper are the angularly disposed members 32 and 33, which extend flaringly apart from the lower edges of the members 28 and 29, respectively, and at right-angles thereto. Located below and substantially parallel with members 32 and 33 are the dividing boards 34 and 35. From the above it will be seen that I have formed two chutes leading from the mouth *h*, one of which leads into the open top of bucket 11, and the other leads into the open top of the bucket 12, all as shown in Fig. 2, from which it will be seen that if the cut-off 30 be turned in one direction that grain which may be in the hopper will be directed into one of the buckets, while if the cut-off be turned in the other direction the grain which may be in the hopper will be directed into the other bucket.

50 The rear of the hopper mechanism is connected to the tops of the rear posts, 3 and 4, by means of the tie 36, which latter is bolted to the rear face of the member 27, with its ends extending out, and after being given a quarter turn, are secured on top of 55 said posts 3 and 4, as shown. Secured across the front of the hopper member 26 is the tie 37 whose end portions are turned forward to where they are given a quarter turn, and they are then secured to the tops of the 60 posts 1 and 2 as shown. By reason of the shape of the tie 37 the hopper is allowed to be located somewhat to the rear of the posts 1 and 2, as shown, in order to allow for other parts which will hereinafter be referred to. Secured on shaft 17 is the wrist 38 which has a finger 39 formed integral therewith, the latter having an eye formed vertically therethrough.

65 Secured on shaft 31 is the wrist 40 which has a finger 41 formed integral therewith, with an eye formed vertically therethrough. The finger 41 is located directly above finger 39, as shown. The fingers 39 and 41 are arranged to be located approximately parallel with each other at all times by means of the connecting-rod 42, the termini of which are disposed in the apertures of said fingers 39 and 41, where they are adjustably retained by means of the respective 70 nuts 43 and 44. The distributor is to be located below and between the two buckets 11 and 12, and it consists of a bottom 45 which is to be disposed at an angle sloping from the rear downward and forward. Extending across between the lower ends of the rear posts 3 and 4 is a rod 46 over which may engage the hooks *m* and *n* which are secured in the rear edge of the bottom 45. Numerals 47 and 48 denote the sides of 75

the distributor, in front of which are located the two chutes 49 and 50. Pivoted at its lower end between the chutes 49 and 50 is the divider 51, with its lower edge slideable on the bottom 45, and its rear end movable to-and-fro between the sides 47 and 48. A handle 52 extends forward from the divider 51, by means of which the divider may be operated manually.

10 Numerals 53 and 54 denote two rods which are pivoted at their lower ends to the sides of the distributor and by which the forward portion of the distributor may be suspended from the weigher.

15 In practice the operation is very simple, for instance: A continuous stream of grain may be deposited in the mouth of the hopper. If the cut-off be turned to the right, as in Fig. 2, then the grain passing 20 from the hopper through the mouth *h* will pass over the member 34 and will fall into the bucket 11, which at this time is raised. Now if the weight 24 be moved out on the bar 23, to notch "50" for instance, then 25 when fifty pounds of grain has fallen into bucket 11 it will overbalance the weight 24, turning shaft 17, and causing the weight 24 to swing over to the left, as in Fig. 3, against the guide 20. When the weight 24 reaches its last named position then the 30 bucket 11 will have moved down to the position in which it is indicated in Fig. 3. When the bucket 11 reaches its last mentioned position then its mouth *c* will be 35 opened, as it will have passed beyond the tie 9, thereby allowing the grain to discharge from bucket 11, through the mouth *c*, onto the bottom 45, from which it will move by gravity to one of the chutes 49 or 40 50. As bucket 11 moves down it is manifest that its consort, bucket 12, will move up, reaching its highest limit coincident with the bucket 11 reaching its lowest limit of movement. The movements of the 45 buckets, as stated, will of course turn to shaft 17 which evidently will move the rod 42 downward thereby turning shaft 31 which will cause the cut-off to turn to the opposite position, that is closing the way to 50 the bucket 11 and at the same time opening the way to bucket 12, thereby causing the latter to fill while the former is emptying. It will be observed that these movements are entirely automatic within themselves, the operations being accomplished 55 without the application of outside power, the weight of the grain being weighed or measured providing the requisite power for the various operations as set forth. By 60 means of the handle 52 the attendant may move the divider to the right or to the left as desired, in order to cause the grain to pass through chute 49 or 50.

I would have it understood that various changes may be made in several details of construction, from that herein shown and described, without departing from the spirit of my invention or sacrificing any of the advantages thereof.

Having now fully shown and described my invention, and the best means for its construction to me known at this time, what I claim, and desire to secure by Letters Patent of the United States, is—

1. An automatic grain weigher comprising a frame, a pair of buckets mounted to slide up and down in said frame, a sprocket chain connecting the buckets, a shaft located central of and above said buckets, a sprocket-wheel mounted on said shaft with said chain disposed thereover, a scale-bar secured to and extending upward from said shaft, a weight adjustably secured on said bar, guides for holding the weight in its extremes of movement, a hopper, a cut-off for distributing the grain from the hopper to first one and then the other of said buckets, means for automatically operating said cut-off by the operation of said shaft, and means for retaining the grain in the buckets until the buckets have been lowered.

2. An automatic grain weigher comprising in combination a pair of counterbalanced buckets adapted to be moved up and down alternately, a rotatable shaft supporting both of said buckets, a sprocket wheel secured on said shaft, a sprocket chain operative over said wheel with its ends secured each to one of said buckets, a frame work supporting all of said parts, guides controlling the vertical movements of said buckets, a hopper disposed above the buckets and having chutes leading therefrom to each of said buckets, a cut-off adapted to deflect the grain from the hopper into one of said buckets, automatic means for operating said cut-off, means whereby the outlet from each of the buckets is closed at all times except when the buckets are near their lowest positions, a block 17 secured on the forward end portion of said shaft, a scale-bar 23 extending upwardly from said block, a weight 24 slidably mounted on said scale-bar, means for securing said weight at various points along said scale-bar, cushions carried by the sides of said weight, and upwardly flaring guides against which said cushions are adapted to contact, all substantially as shown and described.

In testimony whereof I have hereunto 120 subscribed my name to this specification in presence of two subscribing witnesses.

WILLIAM F. HILFIKER.
